UNITED STATES PATENT OFFICE

FRANKLIN R. WHITE AND JOHN J. WOOSTER, OF WATERBURY, CONNECTICUT, ASSIGNEES TO THE PATENT BUTTON COMPANY, OF WATERBURY, CONNECTICUT, A CORPORATION OF CONNECTICUT

FLEXIBLE BUTTON

Application filed November 3, 1930. Serial No. 493,135.

Our invention relates to new and useful improvements in buttons, and more particularly to the flexible type of button.

As is well known to those skilled in the art, it is often desirable to have a button wherein the head may move vertically and also tilt slightly or cant when lifted with the fingers, as this makes it easier to slip the button through the button hole. This is especially so when the button is to be used on work garments, such as overalls and other forms of work suits.

One of the objects of the present invention, therefore, is to produce a flexible type of button that will be extremely cheap to manufacture and assemble, such button consisting of but two parts, that is, the button head and eyelet, after which to attach the button a tack will be driven into the eyelet 10 to hold the button to the material of the garment.

Still another object of the invention is to produce a button of but two parts, each of the parts, in turn, being simple in construction, easily made and the parts capable of quick assembly.

Still another object of the invention is to provide a button formed of but a head and eyelet and the head capable of flexing, canting, or tilting with respect to the eyelet.

With these and other objects in view, the invention consists in certain new and novel arrangements and combinations of parts, as will be hereinafter more fully described and 30 pointed out in the claims.

Referring now to the drawings showing a preferred embodiment of our invention.

Fig. 1 is a sectional view showing the head of the button in its uppermost position with 40 relation to its eyelet and before the tack is inserted;

Fig. 2 is a similar view showing the button head in its lowered or normal position with relation to the eyelet, and the tack being driven through the cloth and the eyelet to hold the button to the cloth;

Fig. 3 is a bottom plan view of the eyelet.

Referring now more specifically to the drawings, there is shown a button head 1 which is preferably made of aluminum, or

might even be made of a hard metal, and is slightly convex on its upper surface 2 and having a slightly tapered rim 3. There is also a hollow hub 4, the lower edge of the hub being crimped or forced inwardly, as at 5, after the hub has been placed over an eyelet 6, which eyelet will shortly be described.

This bottom head may be made from an aluminum slug or wire, which manner of making is very well known in the art and when made in this manner is extremely cheap to manufacture.

It will also be understood that there might be an ornamentation or insignia pressed in the upper surface 2 of the button head, if desired, or, on the other hand, it may be left plain.

This button head 1 is generally made in a button machine, the head being subjected to one or two operations of the dies. Thus, it 70 may be readily seen that the button head is an extremely cheap one to manufacture.

Now the hollow hub is domed, as at 7, as it is this dome surface 7 that causes the mutilation or rounding of the prong 8 of a tack 75 9, which is driven up into the eyelet to hold the button in place.

Referring to the other part of the button, that is, the eyelet 6, this is to be made of a relatively cheap metal and also consists of 80 a hollow hub 10, and the base 11, the base extending upwardly to the point 12 and then downwardly and inwardly to form the rim 13, as may be readily seen in the several views.

The upper edge of the hub is flared slightly upwardly to form the rim 14 and the diameter across the hub and its rim 14 is such that it will just slidingly fit within the hollow hub 4 of the button head. After the parts are placed in position, the lower edge of the walls of the hub will be crimped or forced inwardly so that the upward movement of the button head with respect to the 95 eyelet is limited.

It is also to be noticed that the curvature of the crimped walls of the hollow hub correspond to the upward curvature of the base of the eyelet, so that when the button head 100

is in its lowermost position, as shown in Fig. 2, there is a perfect nesting of the parts.

It will be understood that although the lower edge of the button is crimped about the hub of the eyelet it is not crimped so tightly but that the head may move vertically with respect to the eyelet and may even cant or slightly tilt with respect to the eyelet.

Of course, the eyelets may be made in one machine and the button heads in another, and the head crimped to the eyelet in still another machine.

These buttons are all attached by an automatic attaching machine (not shown) and it will be understood that the buttons are placed in one hopper and the tacks in another, then the cloth 15 will be run through the machine (not shown), and the tack 9 will have its prong driven upwardly through the cloth, through the hollow hub of the eyelet, and impinge against the dome of the head and will be guided and mutilated to assume the position seen in Fig. 2.

Thus, the button head, through the medium of the eyelet and tack, will be tightly held to the cloth, while, at the same time, the button head may be moved vertically or cant with respect to the eyelet, thus making it easier to slip through a button hole.

The base of the eyelet with its rim provides a maximum contacting surface for the cloth and the relatively large head of the tack will thus tightly clamp the cloth between the eyelet and the tack, thus making it nearly impossible to tear the button from its place on the cloth. Likewise, although the button head itself may move it cannot be disengaged from the eyelet.

We are aware that it is old to make flexible type of buttons, and we do not broadly claim our invention as such, but we are not aware of any buttons that are as simply constructed or as easily assembled or as cheap to manufacture and with such few operations thereon, as the present button.

Having thus described our invention, what we claim as new and desire to secure by Letters Patent is:

1. A two-piece flexible button comprising a solid head, a hollow dome-shaped hub, a single-piece eyelet having a flared upper edge and a flared base, the lower edge of the hub crimped beneath the upper edge of the eyelet, the dome-shaped hub adapted to deflect the prong of a tack over the flared rim of the eyelet to thus hold the button to the material to which it is to be attached.

2. A flexible button comprising a one-piece closed top button head having a hub, a one-piece eyelet having a flared upper rim, the lower edge of the hub crimped beneath the rim of the eyelet whereby the head may move slightly with respect to the eyelet, the eyelet having a base that extends slightly upwardly and outwardly to thereby nest the lower

edge of the hub of the button head, the end wall of the hub of the button adapted to receive and mutilate the end of a tack, and the eyelet adapted to have the mutilated end of the tack bear thereagainst to hold the eyelet in position when attached to a material.

3. A flexible button provided with a one-piece closed top button head, a one-piece eyelet slidably fitted within the button head but held against detachment therefrom, a tack mutilated within the button head and extending over a portion of the eyelet whereby the eyelet is rigidly held to the material to which it is attached and the button head capable of movement with respect to the eyelet.

4. A flexible button comprising a one-piece head having a hub, an eyelet fitting within the hub, and the eyelet provided with a flared upper edge, the lower walls of the hub being crimped beneath the flared rim of the eyelet, the base of the eyelet extending upwardly and outwardly and then downwardly and inwardly to form a rim, and the lower edge of the hub nesting in the base of the eyelet, the hub and flared upper rim of the eyelet adapted to receive the mutilated end of a tack to thereby hold the eyelet rigidly in position but to allow the head to flex with respect to the eyelet.

In testimony whereof we affix our signatures.
